CLAIM

The ornamental design for a bicycle headlight, as shown and described.

DESCRIPTION

FIG. 1 is an isometric view of a light in accordance with the new design;

FIG. 2 is front elevational view thereof;

FIG. 3 is a rear elevational view thereof;

FIG. 4 is left side elevational view thereof;

FIG. 5 is a right side elevational view thereof;

FIG. 6 is a top plan elevational view thereof;

FIG. 7 is a bottom plan elevational view thereof; and,

FIG. 8 is a rear elevational view as shown in FIG. 3, showing an opened access port, which is shown closed in FIG. 3. Broken lines in figures are for illustrative purposes only and form no part of the design.
